CLAIM

The ornamental design for a tire sidewall, as shown and described.

DESCRIPTION

FIG. 1 is a perspective view of a tire sidewall showing our new design; and,

FIG. 2 is a front elevational view thereof.

In the drawings, the broken lines showing of the tire tread, inner bead and the peripheral boundary between the tire tread and the tire sidewall in FIGS. 1 and 2 depict environmental subject matter and form no part of the claimed design.
